UNITED STATES PATENT OFFICE.

LEWIS D. WEEKS, OF SANTA MARGARITA, CALIFORNIA.

DESIGN FOR AN EGG-CASE FILLER.

SPECIFICATION forming part of Design No. 35,672, dated February 4, 1902.

Application filed September 3, 1901. Serial No. 74,254. Term of patent 14 years.

To all whom it may concern:

Be it known that I, LEWIS D. WEEKS, a citizen of the United States, and a resident of Santa Margarita, in the county of San Luis Obispo and State of California, have made a certain new and original Design for Egg-Case Fillers; and I declare the following to be a full, clear, and exact description of the same, such as will enable others skilled in the art to which it appertains to make and use the invention, reference being had to the accompanying drawings, which form a part of this specification.

Figure 1 is a plan view of one of my fillers. Fig. 2 is a side elevation of the same.

The invention relates to the design or form of an egg-case filler.

As shown in the drawings, the leading or material feature of my design consists of an

egg-case filler of general oblique parallelogram form and having a plurality of cells of regular hexagonal character and adjacent to each other, each cell having two parallel sides perpendicular to a line joining the center of two opposite sides of the parallelogram and having two other parallel sides perpendicular to a line joining the centers of the other two sides of the parallelogram.

What I claim, and desire to secure by Letters Patent, is—

The design for an egg-case filler, substantially as shown and described.

In testimony whereof I affix my signature in presence of two witnesses.

LEWIS D. WEEKS.
